UNITED STATES PATENT OFFICE.

OSWALD S. PULLIAM, OF PITTSBURGH, PENNSYLVANIA, ASSIGNOR TO PITTSBURGH STEEL FOUNDRY COMPANY, OF PITTSBURGH, PENNSYLVANIA, A CORPORATION OF PENNSYLVANIA.

CAR BODY AND UNDERFRAME CONSTRUCTION.

1,074,200.

Specification of Letters Patent. Patented Sept. 30, 1913.

Application filed October 26, 1910. Serial No. 589,134.

To all whom it may concern:

Be it known that I, OSWALD S. PULLIAM, a resident of Pittsburgh, in the county of Allegheny and State of Pennsylvania, have 5 invented certain new and useful Improvements in Car Body and Underframe Construction, of which the following is a specification.

An object of my invention is to provide a 10 new and improved car underframe comprising an integral metallic structure whose longitudinal length is substantially the same as the length of the car-body, and whose width is considerably less than the width of the 15 car-body.

A further object of the present invention is to provide a construction comprising an underframe having in an integral metallic structure longitudinally extending members 20 constituting the side-sills and a center-sill of the underframe, and separable end-members supported by the longitudinally extending members.

A still further object of my invention is 25 to provide a construction comprising an integral metallic underframe of the character mentioned, having its side-sills adapted to support longitudinally extending car-body sills and having its center and side- 30 sills provided with means for supporting end-members constituting end-sills of the car-body.

In the accompanying drawings which illustrate applications of my invention, Figure 1 is a side elevational view of a part of a car and underframe embodying my invention; Fig. 2, a plan view of the underframe and portions of the longitudinally extending sills and end-member of the car-body, 40 the latter being shown in dotted lines; Fig. 3, a side elevational view of the underframe; Fig. 4, a sectional view taken on line IV—IV of Fig. 2; Fig. 5, a detail end view of the underframe and separable car member; Fig. 6, a sectional view taken on line 45 VI—VI of Fig. 2; Fig. 7, a perspective view of the underframe of a larger size than that shown by the form of Fig. 1, and Fig. 8, a detail view showing a modified form of car body and underframe construction from 50 that shown in the form of Fig. 1.

Referring to the drawings, and first to the form of Fig. 1, which illustrates my invention embodied in a four-wheel railway caboose

construction 2 designates the side-sills or side 55 longitudinal members of the car-body, and 3 and 4 intermediate longitudinally extending sills, and 5 separable cross end-members constituting end-members of the car-body and end members of the car-body under-frame. The members mentioned may be constructed of wood or metal. I prefer wooden members, but it is evident that metal members may be employed. The car-body ends 6, the sides 7, and the floor 8 are built 60 up in the usual manner.

My underframe for the car illustrated by Fig. 1 or for other forms of cars is preferably formed of an integral cast-metal structure and comprises a center-sill 9 extending 70 substantially the full length of the car and formed at each end with projecting members 10 designed to extend under and support the separable end-members 5. The integral underframe also comprises side-sills or side-members 11, said sills having free or non-connected ends and each preferably constituting a member of considerable depth. The free ends of said sills are each provided with a projecting supporting or bearing member 80 12 adapted to extend under and support the separable end-members 5. Members 11 are provided with flat bearing faces 13 adapted to receive and support the respective longitudinal members 3. The side-members 11 85 are connected with the center-sill by cross-members 14 and diagonal members 15, the latter having a plate member 16 formed with projections 17. The projections 17 are designed to enter the respective sills 4 90 of the car-body and the plate members 16 are adapted to act as a support for said sills 4. The length of the metallic underframe is substantially the same as the length of the car but of considerably less width. I have 95 shown pedestals 18 formed integral with the side-members of the underframe. These pedestals, however, and the hangers 19 and 20 may be separable and secured to said side-members.

The underframe of the form of Fig. 1 is 100 designed to be supported by the pedestals 18 in place of being supported upon truck bolsters as is the usual and well known construction.

In the form of my invention illustrated by Fig. 7, I have shown an underframe 105 designed for much larger car-bodies than that

shown in the form of Fig. 1, and in this instance have shown the integral underframe having its center-sill provided with a center-plate bearing 21 adapted to rest upon the 5 center bearing 22 of a truck-bolster.

What I claim is:—

1. The combination, with a car under-frame comprising an integral metallic structure including a center-sill and parallel side-sills, said sills having free non-connected end-portions with the end-portions formed with bearing members, diagonal members projecting from the center-sill toward the ends of the respective side-sills and 10 merging with the side-sills at points short of the ends of said sills, separable car-body end-sills supported by the projecting members and extending beyond the side-sills of the underframe, car-body side-sills supported by 15 the separable end-sills, and intermediate car-body sills supported by the diagonal members.
2. The combination, with a car under-frame comprising an integral metallic structure including a center-sill and parallel side-sills, said sills having free non-connected end-portions with the end-portions formed 20 with bearing members, diagonal members each formed with a sill bearing member, 25 said diagonal members projecting from the center-sill toward an end of the respective 30

side-sills and merging with the side-sills at points short of the ends of the said side sills, separable car-body end-sills supported by the projecting members and extending 35 beyond the side-sills of the underframe, car-body side-sills supported by the separable end-sills, and intermediate car-body sills supported on the sill bearing members of the diagonal members.

3. The combination, with a car-body having side-sills, intermediate sills, and end-sills, said end-sills adapted to support the side-sills, of an underframe comprising an integral metallic structure of less width 40 than the car-body, said underframe including a center-sill, side-sills, diagonal members projecting from the center-sill toward an end of the respective side-sills and merging with the side-sills at points short of the 45 ends of said side-sills, and pedestals formed integral with the side-sills, said center and side-sills having projecting supporting members for the car-body end-sills, and the diagonal members having bearings for the car-body intermediate sills.

In testimony whereof I affix my signature in presence of two witnesses.

OSWALD S. PULLIAM.
